UNITED STATES PATENT OFFICE.

FRANCIS C. KOENIG, OF PHILADELPHIA, PENNSYLVANIA, ASSIGNOR TO
REINHOLD G. LEDIG, OF SAME PLACE.

DESIGN FOR A TABLE.

SPECIFICATION forming part of Design No. 22,708, dated August 15, 1893.

Application filed April 18, 1893. Serial No. 470,898. Term of patent 3½ years.

To all whom it may concern:

Be it known that I, FRANCIS C. KOENIG, a subject of the Emperor of Germany, (having resided one year last past in the United States 5 and declared my intention of becoming a citizen thereof,) residing in the city and county of Philadelphia, State of Pennsylvania, have invented and produced a new and original Design for a Table, of which the following is 10 a specification, reference being had to the accompanying drawing, forming part thereof.

The leading feature of my design for a table is the ornamentation below the top, at the upper end of the leg portions thereof, the same 15 being the representation of a human head with a crown thereon, a scroll above said crown, scrolls extending from the sides of said head to the corners of the table, a spray of flowers depending from said head, and flowers on the 20 sides of said spray having stems which depend from said scrolls.

In the drawing: A designates the representation of a human head with a crown B thereon, and scrolls C above the latter. D designates scrolls which extend laterally from the head A, and E designates a spray of flowers which extend downwardly and join the flowers F at the side of said spray, the stems F' of said flowers F depending from the side scrolls D. The said head, scrolls and flowers 25 are below the top G of the table, and at the upper ends of the legs H thereof.

What I claim is—

The design for a table, substantially as shown and described.

FRANCIS C. KOENIG.

Witnesses:

JOHN A. WIEDERSHEIM,
A. P. JENNINGS.
